(57) **CLAIM**

The ornamental design for a biomolecule transfer device as shown and described.

DESCRIPTION

FIG. 1 illustrates a front, right perspective view of the biomolecule transfer device, shown in a closed configuration;

FIG. 2 illustrates a front elevation view thereof;

(Continued)

FIG. 3 illustrates a rear elevation view thereof;
 FIG. 4 illustrates a right side elevation view thereof;
 FIG. 5 illustrates a left side elevation view thereof;
 FIG. 6 illustrates a top plan view thereof;
 FIG. 7 illustrates a bottom plan view thereof; and,
 FIG. 8 illustrates a front, right perspective view of the biomolecule transfer device of FIG. 1, shown in an open configuration for clarity of disclosure.
 The broken lines in the drawings depict portions of the biomolecule transfer device that form no part of the claimed design.
